(57) **CLAIM**

The ornamental design for a hedge trimmer, as shown and described.

DESCRIPTION

FIG. 1 is a perspective view of a hedge trimmer showing my new design.

FIG. 2 is a side view of a hedge trimmer according to FIG. 1.

FIG. 3 is a top view of a hedge trimmer according to FIG. 1.

FIG. 4 is a bottom view of a hedge trimmer according to FIG. 1.

FIG. 5 is a front view of a hedge trimmer according to FIG. 1; and,

FIG. 6 is a rear view of a hedge trimmer according to FIG. 1.

In the above drawings the broken lines and the areas within the broken lines form no part of the claimed design.
